UNITED STATES PATENT OFFICE

2,639,369

MERCURY SWITCH ACTUATING MECH-
ANISM FOR STAND LAMPS

Earl S. Boynton, East Orange, N. J.

Application November 30, 1948, Serial No. 62,629

4 Claims. (Cl. 240—123)

1

This invention relates to electric light fixtures, and particularly to table lamps and the like and an improved means for actuating the switch means of such lamps.

It is one of the objects of the invention to provide an improved electric light fixture having an improved switch means incorporated therewith which is actuated to light or extinguish the lamp thereof by rotatable means carried by the fixture.

It is another object of the invention to provide an improved electric light fixture having an electric switch incorporated therewith which may be conveniently assembled in the fixture, and which may be entirely concealed thereby enhancing the appearance of the fixture.

It is a further object of this invention to provide a light fixture which is simple and inexpensive in its construction and, at the same time, efficient and effective in its use.

It is still another object of the present invention to provide an improved electric light fixture which is streamlined and neat in appearance having switch means incorporated therewith which may be easily and conveniently actuated to light or extinguish the lamp thereof.

Various other objects and advantages of this invention will be more apparent in the course of the following specification, and will be particularly pointed out in the appended claims.

In the accompanying drawings, there is shown for the purpose of illustration, a preferred embodiment and a modification thereof which my invention may assume in practice.

In these drawings:

Fig. 1 is an elevational view, partly in section, of my improved light fixture;

Fig. 2 is a sectional view taken on line 2—2 of Fig. 1;

Fig. 3 is a sectional view taken on line 3—3 of Fig. 1;

Fig. 4 is a top view of my light fixture with the lamp shade removed; and

Fig. 5 is an elevational view, partly in section, of another embodiment of the present invention.

Referring more particularly to the drawings, the preferred embodiment of my improved light fixture, as shown in Figs. 1, 2, 3, and 4, comprises a base 2, preferably of a hollow construction, having a top 3 and a reduced cylindrical-shaped portion 4 extending upwardly therefrom in which there is arranged a threaded lamp socket 5 for the reception of a suitable electric bulb or lamp 6.

There is carried by and attached to the under side of the top 3 of the base 2, a pair of spaced-

2

apart bracket-like upper bearing portions 7—7 which extend down into the hollow portion of the base. On the bottom of the base, there is provided a bottom closure plate 8 on which there is mounted a U-shaped lower bearing bracket portion 9 positioned directly below the bearing portions 7—7. Between the bearing portions 7—7 and 8, there is a mounted rotatable switch means consisting of a stud shaft 10 having a collar 12 and an upwardly extending lever-like portion 13 integrally arranged therewith. The lever-like portion 13 is in the form of a segmental gear having teeth 14 arranged on the upper end thereof, which lever-like portion is disposed between the pair of bracket portions 7—7, as clearly shown in Figs. 1 and 2.

On the inner end of the stud shaft 10, there is arranged horizontally a small mercury type switch 15 whereby oscillation of the shaft 10 causes the mercury 32 in the tube to flow from one end to the other in the tube to successively make and break the electric circuit in which the lamp 6 is connected to a source of power, as shown. It will be understood that any other suitable type of switch may be employed, if desired, but it has been found that a mercury type switch is most satisfactory.

On the top 3 of the base 2, there is movably mounted an annular member 16 which encircles the upwardly extending cylindrical portion 4 of the base and is rotatable relative thereto. There is arranged on the bottom of the annular member 16, an annular gear-like portion 17 having teeth 18 which fit preferably in an annular groove or race 19 arranged in the upper surface of the base top 3 around the cylindrical portion 4 concentric therewith.

The upper end of the lever-like portion 13, together with the teeth 14 thereof, extend up through an aperture 20 in the top 3 of the base which communicates with the annular groove or race 19 with the teeth 14 meshing with and cooperating with the teeth 18 carried by the rotatable annular member 16 to light and extinguish the lamp in a manner hereinafter to be described.

There is mounted on the annular member 16, a lamp shade 21 consisting preferably of a tubular chimney-like portion 22 which is preferably secured to the member 16 having an upper reduced portion 23 on which there is arranged a suitable shade portion 24. It will be understood that the shade may be of any suitable design, and that the form illustrated possesses desirable artistic characteristics and structural advantages.

Both the lamp portions 22 and 24 are made preferably of a transparent or translucent material, such as glass, molded plastic, or the like, whereas the base and other parts may be made of metal or also preferably of a molded plastic material, such as polystyrene, which will provide a pleasing contrast and artistic effect.

The improved lamp of my invention operates in the following manner. As has been hereinbefore described, the annular member 16, together with the shade 21 carried thereby, is removably and rotatably mounted on the top 3 of the base 2 with the annular gear-like portion 17 positioned in the annular groove or race 19 in the base top. In such position, the teeth 18 of the annular member mesh with the teeth 14 of the lever-like member 13. By such arrangement, it will be seen that when the annular member 16 is rotated manually on the base 2 in one direction that the lever-like member 13 is moved in the direction the annular member is rotated thereby rotating the stud shaft 10 to which it is securely attached. When the shaft is rotated, it will be seen that the mercury 32 in the tube of the mercury switch 15 will flow in the tube from one end to the other end thereof thereby causing the mercury to contact the two electrical contacts 33-33 disposed in that end of the tube so as to complete the electrical circuit through the lamp 6 to light the same. Thus, it will be seen that when the annular member 16 is rotated on the base in the opposite direction, the lever-like member 13 is moved in the opposite direction and, likewise, the stud shaft 10 is moved in the same direction thereby causing the mercury 32 in the mercury switch 15 to move to the opposite end of the tube and out of contact with the electrical contacts 33-33 thereof thereby breaking the circuit so as to extinguish the lamp 6.

In Fig. 5 of the drawings, there is shown a modification of the light fixture in accordance with my invention. The construction of this embodiment is substantially the same as that of the preferred form, except that the lamp shade 30 is mounted in a conventional manner by a spring snapping arrangement on the lamp or bulb 31 of the fixture instead of on the annular rotatable switch actuating means thereof, as in the preferred form. In this construction, there is provided an annular member 25 similar to the annular member 16 mounted on the top of a base 26 around a reduced portion 27 of the base. The upper end of the reduced portion 27 is preferably threaded, as at 28, and a threaded collar 29 is disposed thereon to hold the annular member 25 in position on the base. There is arranged with the annular member 25, a gear-like portion as in the preferred construction which cooperates with a lever-like portion arranged with a mercury switch in the same manner as the preferred construction for actuating the switch. The switch construction and operation of this modified form is identical with the preferred form so any further description of this construction and operation of the same is believed unnecessary.

As a result of my invention, it will be seen that there is provided an improved lamp fixture which is not only neat appearing, but extremely simple and inexpensive in its operation and construction. It will be seen also that all the parts of my light fixture, with the exception of the switch means, may be easily and conveniently molded or fabricated from a suitable plastic material. Also, the mercury switch means of my light fixture is simple and inexpensive, and one consisting of a minimum number of parts which will operate indefinitely without failure or maintenance.

While I have shown and described several embodiments which my invention may assume in practice, it will be understood that these embodiments are merely for the purpose of illustration and description, and that other forms may be devised within the scope of my invention as defined in the appended claims.

What I claim as my invention is:

1. An electric light fixture of the class described, comprising a hollow base, an electric lamp mounted on said base, an electric switch arranged in said base for said lamp and in an electric circuit therewith, a lever-like member oscillatively mounted in said base for actuating said switch, an annular groove arranged in the upper surface of said base, said groove having an opening therein through which said lever-like member extends into said groove, an annular member rotatably arranged in said groove which cooperates with the upper end of said lever-like member to actuate the same whereby said switch is adapted to close when said annular member is rotated in one direction and to open said switch when rotated in the opposite direction.

2. An electric light fixture of the class described, as defined in claim 1, wherein the annular member is arranged integral with a lamp shade rotatably mounted on said base.

3. An electric light fixture of the class described, as defined in claim 1, wherein both the annular member and the lever-like member are gear-like members with the teeth of one cooperating with the teeth of the other.

4. An electric light fixture of the class described, as defined in claim 1, wherein the electric switch is mercury actuated.

EARL S. BOYNTON.
